UNITED STATES PATENT OFFICE.

GEORGES CADET, OF PARIS, AND FERNAND CHARLES LEON DELATTRE, OF PARC DE ST. MAUR, FRANCE.

ROTARY PRINTING-MACHINE.

1,271,525.

Specification of Letters Patent.

Patented July 2, 1918.

Application filed January 30, 1914. Serial No. 815,493.

To all whom it may concern:

Be it known that we, GEORGES CADET and FERNAND CHARLES LEON DELATTRE, both citizens of the Republic of France, and residing, respectively, 20 and 22 Rue du Mail, Paris, France, and 68 Avenue Marigny, at the Parc de St. Maur, Seine, France, have invented certain new and useful Improvements in Rotary Printing-Machines, of which the following is a specification.

The present invention relates to rotary machines called "Duplex-Tubular" machines known in connection with the printing of newspapers in one color. The object of the invention is the adaptation of these machines to printing in several colors which are either simple side by side, or composite and obtained by the printing of simple colors one over another.

As is known, Duplex Tubular machines for printing in one color are composed of several sets each of which comprises two stereotype cylinders. Paper webs coming from reels in number equal to the sets of the machine pass one into each of the sets and receive on both sides the print in one color.

The invention is characterized by the fact that the webs of paper issuing from particular reels pass successively through two or more sets of the machine where they receive impressions in different colors. This modification necessitates the addition of turning or reversing rollers and means for effecting the register of the successive impressions.

These means consist in:

1. Adjusting clamps permitting the regulation of the stereotype plates in a transverse direction with reference to the paper web.
2. Adjusting apparatus for effecting the longitudinal register of the paper web with reference to the stereotype plates.

The annexed drawings show by way of example several ways of carrying out the object of the invention.

Figures 1 to 6 show various combinations possible in a "Duplex-Tubular" machine with four sets for printing a newspaper in several colors.

Fig. 7 shows in elevation a stereotype cylinder provided with its stereotype plates.

Fig. 8 is a section on line 8—8 of Fig. 7.

Fig. 9 is a section on line 9—9 of Fig. 8.

Fig. 10 represents an adjusting device in elevation.

In the combination shown in Fig. 1 a single reel of paper A^1 is employed. The paper web a issuing from this reel traverses successively the sets A, B, C, and D, where it receives impressions in different colors. The paper web a is thus finally printed on both sides in four different colors.

The figure clearly shows the position of the adjusting devices F and of the turning rollers G.

In the combination shown in Fig. 2 two reels A^1 and B^1 are used. The web a issuing from the reel A^1 traverses the set A only and receives on both sides the impression in a single color. The web b issuing from the reel B^1 traverses successively the sets B, C, and D and receives therefore on both sides the print in three colors.

The combination shown in Fig. 3 comprises three reels A^1 , B^1 and C^1 . The paper web a issuing from the reel A^1 traverses only the set A, of the machine and receives the print on both sides in one color. The same thing happens with the web b issuing from the reel B^1 which traverses only the set B. The web c issuing from the reel C^1 traverses successively the two sets C and D and receives the impression in two colors on its two sides.

In the combination shown in Fig. 4 two reels C^1 and D^1 are used. The web c issuing from the reel C^1 traverses successively the sets C and A of the machine and receives on both sides the impression in two colors. The web d issuing from the reel D^1 traverses successively the sets D and B and receives on both sides the impression in two colors.

The combination shown in Fig. 5 in the same way comprises two reels A^1 and C^1 . The web a issuing from the reel A^1 only traverses a single set A and receives on both sides the impression in one color, while the

web *c* issuing from the reel *C*¹ traverses successively the sets *C*, *D* and *B* and receives the impression in three colors on its two faces.

- 5 The combination shown in Fig. 6 comprises again two reels *C*¹ and *D*¹. The web *c* issuing from the reel *C*¹ traverses successively the sets *C*, *A* and *B* and receives the impression in three colors on both sides.
- 10 The web *d* issuing from the reel *D*¹ only traverses the set *D* and consequently receives the impression in one color only on its two sides.

In the combinations shown in Figs. 1, 2, 3
15 and 5 the tape beds or supports *X* which are usually stretched horizontally between the sets *A* and *B* on one side and *C*, and *D*, on the other are retained and serve, in case of the breakage of the web passing between
20 the upper printing rolls *C* and *D*, to prevent the loose ends from falling into and fouling the lower rolls *A* and *B*.

In the combinations shown in Figs. 4 and 6 the tape beds are suppressed since one of
25 the paper webs crosses the usual position of the beds.

It is plain that for printing a newspaper the use of one or other of the combinations proposed effects the color printing on different pages for each combination.

It is obviously also possible to use either the combination of Fig. 5 or that of Fig. 6 both of which allow the printing of 8 full size pages four of which are in one color
35 and four in three colors.

In point of fact in the case of Fig. 5 the pages printed in one color are pages 3, 4, 5 and 6, and those printed in three colors are pages 1, 2, 7 and 8 while in the case of Fig.
40 6 it is the pages 1, 2, 7 and 8 which are printed in one color and the pages 3, 4, 5 and 6 which are in three colors.

It is known that in ordinary machines of the "Duplex-Tubular" type two stereotype
45 plates are mounted on each cylinder *e*. One of the plates *h* abuts against a collar *e*¹ (Figs. 7, 8 and 9) with a chamfered edge carrying with it by means of bent metal wires *i* the dogs *i*¹ which ride up inclined
50 planes and which are applied to the edge of the plate *h* on the side opposite to the ring or collar *e*¹. The second plate *h*¹ is held between the dogs *i*¹ on one side and the dogs *i*² on the other side.

55 To allow of the transverse regulation of the plates with reference to the paper web according to our invention we have made the two portions *e*² of the ring *e*¹ movable. Each part or clamp *e*² (see particularly Fig.
60 9) is furnished with a screw threaded hole in which engages a screw *e*³ rotatably movable, but held at its two ends. On turning the screw *e*³ in one direction or the other the clamps *e*² are moved and in consequence the

position of the plates on the surface of the 65 cylinders is modified.

Fig. 10 shows one of the adjusting devices F used for the longitudinal regulation of the paper web with reference to the stereotype plates. *f* is a roller mounted in a fixed position on a trunnion in the frame *f*¹. *f*² is a roller mounted on trunnions in the ends of two arms *f*³ fast with the axis of the roller *f*. The axis of the roller *f*, also carries an arm *f*⁴ at the extremity of which is pivoted 70 a screw nut *f*⁵ in which screws a threaded member *f*⁶. The threaded member *f*⁶ is provided with a hand wheel *f*⁷ and two collars *f*⁸ situated one on either side of a socket *f*⁹ pivoted on the frame *f*¹. When the hand wheel *f*⁷ is turned the position of the roller *f*² is altered, which alteration changes the length of the path of the paper web *a*. The arms *f*³ can be set on the axis of the roller *f* inclined at some angle to the arm *f*⁴. The 75 turning rollers *G* are of the usual type.

It is very evident that the invention is not limited to the combinations which have just been described. Furthermore the arrangements according to the invention are applicable to every "Duplex Tubular" or analogous rotary machine with multiple sets, whatever be the number of sets.

What we claim and desire to secure by Letters Patent of the United States is:— 95

1. In a rotary printing press, a web take-up device comprising a stationary guide roll over which the web passes, an adjustable take-up roll pivoted on the axis of the stationary roll, and manually operated means 100 for swinging the take-up roll on its axis to regulate the length of the path of travel of the web.

2. In a rotary printing press, a web take-up device comprising a fixed guide roll, a pair of levers fast with the axis of the guide roll, a take-up roll journaled between said levers, an adjusting lever also fast with said axis, and manually operated means 105 engaging said adjusting lever to alter the position of said take-up roll and thus regulate the length of the path of travel of the web.

3. In a rotary printing press, a web take-up device comprising a fixed guide roll, a pair of levers fast with the axis of the guide 110 roll, a take-up roll journaled between said levers, an adjusting lever also fast with said axis, and a manually operated screw engaging the end of said adjusting lever to alter the position of the take-up roll and thus 115 regulate the length of the path of travel of the web.

4. In a rotary printing press, a series of printing units, through which the printing web successively passes, and a regulating device engaging said web between the units, said device comprising a stationary guide roller 120 over which the web passes directly to one of

the units, a displaceable roller pivoted on the axis of the stationary roller and engaging the web in advance of the latter and means for swinging said pivoted roller on its axis 5 to vary the length of the path of travel of the web between the printing units, for the purpose described.

In testimony whereof we have signed our

name to this specification in the presence of two subscribing witnesses.

GEORGES CADET.

FERNAND CHARLES LEON DELATTRE.
